UNITED STATES PATENT OFFICE.

WILLIAM G. KIRCHHOFF, OF CINCINNATI, OHIO, ASSIGNOR TO THE J. H. DAY COMPANY, OF CINCINNATI, OHIO, A CORPORATION OF OHIO.

COMBINED BLENDING AND SIFTING DEVICE.

Application filed August 14, 1924. Serial No. 732,072.

My invention relates to a device for blending and mixing various products, generally in the pulverized form, whereby to effect an even mixture of the products in variable proportions.

An object of my invention is to provide a simple and efficient device for the purpose stated.

Another object of my invention is to provide means whereby a minimum of operations and a minimum number of handlings of the various commodities are required, for effecting the blending and the sifting of the substances.

These and other objects are attained by the means described herein, and disclosed in the accompanying drawings, in which:

Fig. 1 is a front elevation, parts being broken away, of the device embodying my invention.

Fig. 2 is an enlarged end elevation, parts being broken away, of the device shown in Fig. 1.

Fig. 3 is an enlarged sectional view on line 3—3 of Fig. 1.

Fig. 4 is an enlarged sectional view on line 4—4 of Fig. 3.

Fig. 5 is an enlarged sectional view on line 5—5 of Fig. 2.

Fig. 6 is an enlarged sectional view on line 6—6 of Fig. 1.

The device of my invention comprises a pair of bins 10 and 11, adapted to discharge from their lowermost portions through a suitable feed structure, shown generally at 12 in Fig. 6, into a trough 13 extending below both of the bins and containing a spiral screw 14. The trough 13 together with the screw 14 constitutes a substantially horizontal conveyor that discharges into the casing 15 of an elevator or elevating conveyor, referred to generally as 16. Suitable elevating means are contained within the casing 15 for carrying the substance from the bottom of the casing 15 upwardly to a conveyor 17, that discharges into a sifting mechanism 18. The conveyor 17 may comprise a suitable casing 19 within which is contained a spiral screw or the like 20. The screw 20 is revolved in any suitable manner, for example from the chain 21 forming part of the elevator 16,

which chain 21, extends about sprockets carried by shafts 22 and 23. The shaft 22 carries the screw 20, and extends into a screen 24 forming part of the sifter 18. The sifter may be mounted on the shaft 22 to revolve therewith, so that the material will be agitated to such extent within the screen 24, so as to pass the material through the screen into a suitable discharge nozzle or duct 25. The nozzle or duct 25 may discharge into a suitable bin or other container, not shown. The shaft 23 extends through the trough 13 and carries the screw 14. The shaft 23 carries means for actuating or driving the agitators 26 associated with the bins 10 and 11 for causing the substance contained within the bins to pass through the perforations 27 provided in the bottoms of said bins. By reference to Figs. 2 and 6, this structure will be readily understood. The structures provided for actuating both of the agitators are identical, wherefore the description of one will suffice for both. Referring to Fig. 2, it will be noted that the shaft 23 carries a gear 28 that drives a gear 29 mounted on a stub shaft 30 supported by suitable brackets 31, extending from the base or frame 32 of the device. A link 33 has its one end pivotally mounted upon the gear 29, said mounting being eccentric to the shaft 30. The other end of the link 33 is pivotally mounted at the outer ends of a pair of cranks 34 having pivotal mountings upon the shaft 35 extending through one of the bins. Externally of the bin the shaft 35 carries a ratchet wheel 36. The ratchet wheel is disposed between the pair of cranks 34. A spring actuated pawl 37 carried by cranks 34 is adapted to co-operate with the ratchet wheel 36 for imparting intermittent rotatory motion to the shaft 35. Means are provided for adjusting the stroke or arc through which the shaft 35 is moved. Said means comprises a plate or disc 38 revolubly mounted on shaft 35 for arcuate adjustment. The plate or disc 38 is provided with a peripheral flange 39 terminating adjacent the pawl 37 and over which the pawl may move. By reference to Fig. 3, and in view of the foregoing explanation, it will be evident that by adjusting the disc 38 so as to expose various numbers of teeth of the ratchet wheel to the pawl 37, the arc

through which the shaft 35 may be moved by the ratchet mechanism, may be modified. The disc 38 is provided with a plurality of slots 40 adapted to receive the bolt 41 that is pivotally mounted upon the frame 32. A nut 42 carried by the bolt 41 serves to fixedly position the plate 38 in various adjusted positions. A suitable locking dog 43 is provided to preclude movement of the ratchet wheel, 10 except in a predetermined direction. The locking dog serves to restrain the ratchet wheel against movement when the pawl 37 is being moved in a clockwise direction, see Fig. 3. A suitable cover or protecting casing 44 may be provided to encase the various mechanisms just described, and a suitable door 45 may be provided in said casing, and through the opening with which said door is associated, access may be had to the bolt 41 15 and disc 38 for adjusting same. Within each of the bins the shafts 35 carry suitable discs 46 between which extend bars 47. The bars are moved through the substance contained within the bin, and move adjacent the openings 27 provided in the lower portions 12 of the bin, thereby serving to discharge the substance from the bins into the trough 13. From the foregoing, it will be readily evident that if the agitator associated with the bin 10 20 moves through an arc twice the size of the arc through which the bin 11 is moved, then the substance will be discharged into the trough 13 in proportions of two parts of the substance in container 10 to one part of the substance within the container 11. It will be observed that as the substance from container 10 moves below the substance in container 11, the substance discharged from container 11 is 25 distributed evenly upon the substance moving from bin 10. It therefore, follows that when this admixture reaches the elevator 16, the mixing process will be carried further, while the parts of the admixture remain constant and practically even. The sifter 18 concludes 30 the admixing of the substances in the desired proportion, and at the same time conditions the admixed substance for the next operation, which, in bakeries would be the making up 35 of dough from the admixture.

Although the invention disclosed herein is primarily intended for use in bakeries, for admixing flour, it will be readily evident that it can be employed to advantage for admixing cement and sand, etc.

The operation of the device is as follows:

Power from the motor 48 is transmitted to the shaft 23. The shaft 23 transmits motion to the individual ratchet mechanisms, thereby agitating the substances within the bins and causing said substances to be discharged into the trough 13. The spiral screw associated with the shaft 23, moves the substances discharged from the bins through the trough 13 into the casing 15. The elevator may be operated directly from the shaft 23 and serves

to carry the admixture to the conveyor 17, from whence the admixture moves to the sifter 18. The admixed substance is removed by way of the conduit 25.

What I claim is:

1. In a flour sifting and blending device the combination of a plurality of bins having relatively elongated discharge openings arranged in closely adjacent end to end relation, a trough extending beneath said opening, agitators in said bins, a shaft in the trough, a conveyor screw on said shaft, adjustable means operable from said shaft whereby to impart differential intermittent rotary movements to the several agitators for effecting discharge of substance over an extended portion of the conveyor screw, the several substances being subjected to mixing during and after discharge, an elevator for receiving the substance driven from and moving in synchronism with the conveyor shaft and a revolving screen member driven from the conveyor shaft whereby the substance from the elevator is uniformly sifted and aerated.

2. A flour blender comprising a plurality of bins having elongated aligned discharge openings, a receiving trough extending beneath said openings, a spiral conveyor adapted to mix and move flour from the discharge openings, agitators in the bins adapted to be driven at various and differential speeds from the conveyor shaft, an elevator receiving from the trough and operated from and in synchronism with the conveyor shaft, a transverse screw conveyor operated from the conveyor shaft and receiving mixed substance from the elevator and a revolving aerating sifter screen connected to the last mentioned screw conveyor.

3. In a device of the class described the combination of an extended trough, a power driven screw conveyor therein, bins adapted to discharge into the trough substantially throughout the length thereof, adjustable agitators driven from the screw conveyor shaft and adapted to feed into the trough, the screw conveyor in said trough serving to mix the discharge from the several bins as the substance is moved along the trough, and a revoluble screen drum operable from the conveyor shaft for uniformly aerating and sifting the substance from the trough.

4. In a combined blending and sifting device the combination of a horizontal conveyor and casing, an elevating conveyor, a horizontal conveyor at the top of the elevating conveyor, a sifter communicating with the last mentioned horizontal conveyor, a series of bins mounted along the casing of the first mentioned casing, each of said bins having perforations communicating with the casing throughout the length of the bins, agitators in said bins, a single power means for actuating all of said conveyors and said sifter

and adjustable means actuated from said power means for providing differential rates of movement to the several agitators.

5. In a blender the combination of a plurality of bins, a conveyor casing receiving discharge from the bins, agitators in said bins, a conveyor comprising a shaft extending through the casing means to continuously

rotate the conveyor shaft and means connecting each agitator with the conveyor shaft and 10 adapted for independent adjustment for regulating discharge from the bins.

In testimony whereof, I have hereunto subscribed my name this 9th day of August, 1924.

WILLIAM G. KIRCHHOFF.
